WIRE HOOK

Ignazio Del Bagno, Belleville, N. J., assignor of
fifty per cent to Mary Del Bagno, Belleville,
N. J.

Application September 12, 1945, Serial No. 615,739

3 Claims. (Cl. 294—26)

1

This invention relates to a wire hook, and more particularly to such a hook adapted for the engagement and positioning of wire as operated upon by a wire drawing machine.

A primary object of this invention is the provision of a hook adapted to engage the wire adapted to be positioned about the rollers and through the dies of a multiple head wire-drawing machine whereby the wire may be positioned without the necessity of the operator placing his hands in the soapy solution surrounding the rollers and dies in a conventional machine of this type.

An additional object of the invention is the provision of such a hook provided with means whereby wire of any desired diameter may be readily grasped thereby.

Still another object of the invention is the provision of such a wire so arranged and constructed that the wire may be bent through the multiple aligned dies of the conventional wire-drawing machine without the necessity of inserting the hands, arms, or any parts thereof into the solution surrounding the rollers and dies at any time.

A still further object of the invention is the provision of such a hook provided with means whereby the same may be readily positioned on the side of the tank containing the solution and retained in position thereon when not in use.

A still further object of the invention is the provision of such a wire so formed and arranged as to facilitate the positioning of the wire through the aligned dies of the machine with a minimum of difficulty and effort.

Other objects will in part be obvious and in part be pointed out hereinafter and shown in the accompanying drawing wherein there is disclosed a preferred embodiment of this inventive concept.

In the drawing:

Figure 1 is a fragmentary top plan view of a multiple die wire-drawing machine disclosing the arrangement of the wire as passed through the dies.

Figure 2 is a transverse sectional view through the tank, rollers, and die holders, disclosing the hook of the instant invention in one position of adjustment.

Figure 3 is a view similar to Figure 2 but disclosing the hook in a different position of adjustment.

Figure 4 is a view similar to Figures 2 and 3 but disclosing the hook in a still further position of adjustment, and

Figure 5 is a top plan view of the hook shown in Figures 2, 3 and 4.

Similar reference characters refer to similar parts throughout the several views of the drawing.

Referring now to the drawing, there is generally indicated at 10 a tank or vat adapted to contain the customary soap and water lubricating solution, generally indicated at 11. Positioned transversely of the vat 10 are a pair of feed rollers 12 and 13, driven in any desired conventional manner (not shown), between which is positioned a die holder 14 suitably supported at the ends of the tank 10, adapted to carry a plurality of pairs of aligned dies 15. The dies may be of any conventional type, and of any desired number in accordance with the particular machine, the hook, comprising the instant invention and to be hereinafter described, being adapted for use with any desired conventional type of wire-drawing machine.

Referring particularly to Figure 1, in the operation of the machine the wire 16 is fed from any suitable desired source in the direction indicated by the arrows 17 toward the first pair of dies 15a, passed through the dies and about the roller 12, thence around the rollers 12 and 13 and through the second pair of dies 15b (see Fig. 1). The wire is then fed through the further pairs of dies until finally emerging from the last set of dies 15c, the wire, now reduced to the desired diameter, leads in the direction of the arrow 18 to any desired reel for storage or the like. Obviously, in replacing the reels containing the wire to be treated, and the final product, and in feeding the wire to the dies, it is necessary that the wire be passed through the soapy solution 11, and heretofore this has been done manually. Due to the fact that the solution becomes hot, and the soap contained therein is frequently of a caustic nature, this operation has been difficult and unpleasant and has frequently resulted in irritation of the arms and hands of the workers. The present invention is designed to reduce the unpleasantness of such task, and to obviate the necessity of placing the hands and arms in the water at any time.

The present invention comprises a wire generally indicated at 20, and including a substantially vertical portion 21 terminating at one end in a reverse bend 22 to provide a vertical portion 23 parallel to the portion 21, which terminates in a looped handle 24 positioned in substantially right angles to the portion 23. At its opposite extremity, the portion 21 is bent, as at 25, to merge into a horizontal portion 26 which, in turn, terminates in a bend 27 of relatively wide radius

adapted to pass about the feed roller 12, as will be pointed out hereinafter, the bend 27 merging into an angularly disposed portion 28 which is crimped, as at 29, to form a notch 30. It will be seen that the notch 30 progressively narrows toward the point 29, in order that any desired diameter of wire may be wedged thereinto and firmly grasped therewithin. At its farthest extremity, the wire terminates in a bend 31 which may form a finger grip. It is to be understood that in the foregoing the terms vertical and horizontal are purely relative, and relate to those sections of the wire which assume vertical and horizontal positions when the wire is arranged as disclosed in Figure 2.

From the foregoing, the method of use of the wire hook should be readily understandable. When not in use, the device may assume the position disclosed in Figure 2 with the upper extremity of one of the side walls of the tank 10 engaging between the portions 21 and 23, thus retaining the wire hook in position ready for operation. The portion 26 will extend beneath the rollers 12 and 13, and the arcuate portion 28 terminating in the wire-gripping jaw 30 will extend upwardly and be positioned above the level of the soapy solution 11 at a point adjacent the dies 15, and slightly thereabove. When it is desired to utilize the device for replacing the wire through the dies, it will be seen that the wire 16 may be wedged into the jaws 30, and the device grasped by the handle 24, lifted from the edge of the tank 10, and moved to the position disclosed in Figure 3, drawing the wire downwardly about the roller 12, and thence toward the operator past the roller 13. The hook 20 may then be lifted clear of the solution to the position disclosed in Figure 4, and the wire drawn upwardly out of the solution. The extremity of the wire 16 may then be grasped by the free hand, and reinserted through the next successive pair of dies 15, and the device re-positioned, as shown in Figure 2, with the jaws 30 adjacent the next successive pair of dies and positioned to have the wire re-grasped therein, whereupon the operation may be successively repeated until the machine is set up and ready for operation. It is to be understood that during this operation the feed rollers 12 and 13 are constantly rotated in order to feed and force the wire through the suc-

cessive dies when the same is positioned in operative relation with respect thereto.

From the foregoing, it will now be seen that there is herein provided an improved wire hook, accomplishing all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

- 15 1. A wire hook comprised of a single piece including a handle, a portion at right angles to the handle, a 180° bend terminating in a portion parallel to said first-mentioned portion, an extending portion, an angularly disposed portion extending upwardly and inwardly with respect to said extending portion, and a wire clamping portion adjacent the extremity of said angularly disposed portion.
- 20 2. A wire hook comprised of a single piece including a handle, a portion at right angles to the handle, a 180° bend terminating in a portion parallel to said first-mentioned portion, an extending portion, an angularly disposed portion extending upwardly and inwardly with respect to said extending portion, and a wire clamping portion adjacent the extremity of said angularly disposed portion, said wire-clamping portion comprising a V-shaped bend in said angularly disposed portion.
- 25 3. A wire hook comprised of a single piece including a handle, a portion at right angles to the handle, a 180° bend terminating in a portion parallel to said first-mentioned portion, an extending portion, an angularly disposed portion extending upwardly and inwardly with respect to said extending portion, and a wire clamping portion adjacent the extremity of said angularly disposed portion, said wire-clamping portion comprising a V-shaped bend in said angularly disposed portion and said angularly disposed portion including an arcuate portion adapted to partially surround a feed roller in a wire-drawing device.

IGNAZIO DEL BAGNO.
